Inventor.

Samuel L. Lord.

United States Patent Office.

SAMUEL L. LORD, OF SURRY, MAINE.

Letters Patent No. 99,922, dated February 15, 1870.

IMPROVEMENT IN BOAT-DETACHING APPARATUS.

The Schedule referred to in these Letters Patent and making part of the same.

To all whom it may concern:

Be it known that I, SAMUEL L. LORD, of Surry, county of Hancock, State of Maine, have invented an Improvement for Holding and Detaching Boats on board Steamships, Sailing, or other Vessels, called "Eureka Boat-Detaching Apparatus;" and I do declare that the following is a full and exact description thereof, reference being had to the accompanying drawings and to the letters of reference marked thereon.

The nature of my improvement consists in providing a cheaper, simpler and more convenient method of detaching a boat from a vessel's side in case of necessity, as in a storm, when the vessel is in danger of sinking and the boat is necessary to preserve life; or when a man is overboard and a boat is wanted without a moment's delay. By means of my invention the boat can be instantly detached.

To enable others skilled in the art to make and use my invention, I will proceed to describe its construction and operation.

In Figure 1, A represents the stern part of the boat. B represents the socket for holding the hook C. C is the hook which holds the boat when confined on board the ship.

D is the bolt which fastens the whole device to the stern post.

E is the lever which confines the hook C and keeps it in its place.

F is the rivet which confines the socket B and lever E to the bolt D.

G is the rivet which confines the hook C to the socket B.

H is the rope which confines the lever E to the block of wood I.

This figure, (1,) represents the whole device at rest on board ship with the boat suspended.

Figure 2 represents the device with the boat detached. The lever E is lifted and the hook C is opened, and thus the boat is released from its confinement.

I do not claim a patent on the hook alone.

What I claim as my invention is—

The arrangement of the socket B and hook C, as combined and arranged with the bolt D, lever E and block I, for the purpose above described and substantially in the manner above set forth.
